UNITED STATES PATENT OFFICE

HARRY C. WAY, OF WHEELING, WEST VIRGINIA

PACKAGING OR CRATING STRUCTURE

Application filed August 19, 1931. Serial No. 558,120.

My present invention relates to improvements in packaging or crating structures of the general character constituting the subject matter of my prior application, serial number 520,395, and my present purpose, generally speaking, is to provide a packaging or crating structure which embodies the fundamental desirable features of my prior structure referred to, and which further embodies other features of advantage both from a production and a utilitarian viewpoint.

A crating structure produced in accordance with the disclosure in my prior application referred to comprises essentially a pair of U-shaped crating elements of U-shaped or channel cross section fitting one within the other and having provision for increasing or decreasing the effective length of the structure. However, said structure lacks provision for varying the effective width thereof and for reinforcement of its corners, and, moreover, requires that the respective elements be formed of different cross sectional sizes for interfitting cooperation. Accordingly, the more important objects of my improvements are—to provide a crating structure composed of crating elements of U-shaped or channel cross section and which is adjustable in width as well as length; which includes corner reinforcements serving also for adjustably connecting together adjacent side and end crating elements, and which embodies side and end crating elements all of which may be of the same cross sectional size.

With the foregoing and various other objects in view, which will become more fully apparent as the nature of the invention is better understood, the same consists in the novel features of construction, combination and arrangement of parts as will be herein-after more fully described, illustrated in the accompanying drawings and defined in the appended claims.

In the drawings wherein like characters of reference denote corresponding parts in the different views:—

Figure 1 is a perspective view of one of the crating elements.

Figure 2 is a perspective view of one of the corner elements.

Figure 3 is a perspective view of a package or crate formed by means of the elements illustrated in Figures 1 and 2.

Figure 4 is a cross section on the line 4—4 of Figure 3.

Figure 5 is a section on the line 5—5 of Figure 3.

Figure 6 is a view similar to Figure 5 illustrating an alternative embodiment of the invention; and

Figure 7 is a cross section illustrating another alternative embodiment of the invention.

Referring to the drawings in detail, it will be observed that my present packaging or crating structure consists essentially of a pair of side crating elements designated as 10, 10, a pair of end crating elements designated as 12, 12, and four corner elements 14 employed to connect the side and end crating elements together.

The side and end crating elements may be of different lengths, but in other respects they are duplicates of one another, each being of U-shaped or channel cross section and comprising a side wall and a pair of lateral flanges 18, 18. They are formed preferably from sheet metal by a rolling or pressing process or in any other suitable or desired manner, and while they may be formed individually, it is preferred to roll, press or otherwise form a blank of elongated form and to thereafter cut this blank into sections of desired length to constitute said elements.

Preferably the lateral flanges 18, 18 of each side and end element are mitered at their ends to permit a rectangular assembly of said elements with the ends of the side walls 16 of the respective side and end elements disposed in abutting or substantially abutting relation, and in accordance with the embodiment of the invention illustrated in Figures 1 to 5, the side wall 16 of each side and end element is provided with a plurality of slits near each end thereof to provide any desired plurality of tongues 20 spaced equidistantly apart longitudinally of said wall.

The corner elements 14, like the side and end elements 10 and 12, are of U-shaped or channel cross section and are duplicates of

one another, each being of angular or substantially L-shaped whereby the right angularly disposed legs or arms thereof are adapted for cooperation with the adjacent 5 ends of one of the side and one of the end elements, respectively, and like the side and end elements said corner elements may be formed either individually or by cutting an elongated blank into sections of desired 10 length.

Each end element initially is straight and composed in cross section of a side wall 22 and a pair of lateral flanges 24, 24, and in accordance with the invention V-shaped 15 notches 26 are formed in the lateral flanges, medially thereof, whereby the element is adapted to be bent into its angular or L-shape aforementioned. Moreover, the sectional size of the corner elements is slightly 20 greater than the sectional size of the side and end elements whereby the legs or arms of the corner elements are adapted to snugly receive and embrace the end portions of the side and the end elements.

25 In the side wall 22 of each of the arms of each corner element is formed a series of narrow slots 28 which are evenly spaced longitudinally of said wall the same amount as the spacing of the tongues 20 for the selective reception of said tongues.

To effect packaging or crating of articles by means of the side, end and corner elements described, the tongues 20 of the side and end elements first are bent to extend outward 35 from said elements. The side elements then are disposed in embracing relation to the sides of the articles, the end elements are disposed in embracing relation to the ends of the articles, and the corner elements are disposed 40 with their leg or arm portions in embracing relation to the end portions of the side and end elements, respectively, with the tongues 20 of the side and the end elements extending through the slots 28 of the related legs 45 of the corner elements, respectively. The tongues then are bent inward against the outer faces of the side walls of the corner elements whereby the side, end and corner elements are locked together in collective embracing relation to the marginal portions of 50 the articles.

Instead of providing tongues on the side and end elements to extend through slots in the corner elements to lock the several elements in assembled relation, the side walls of 55 the side, end and corner elements may be provided with openings 30 for the reception of short bolts 32 as illustrated in Figure 6. In this event the openings in each of said elements all are evenly spaced longitudinally 60 of the respective elements and the openings of the side and end elements are countersunk into the inner faces of said elements to receive the bolt heads, the flat end faces of 65 said bolt heads thus being adapted to lie

flush with or within the planes of the inner faces of the side walls of the side and end elements so as not to engage the packaged or crated articles or to interfere in any way with the complete embracing engagement of the side and end elements with the articles.

Nuts 34 screwed onto the ends of the bolts 28 against the outer faces of the side walls of the corner elements serve to secure the respective elements in assembled relation, 70 and in this connection it is apparent that according to both embodiments of the invention the corner elements are readily removable to release the side and end elements for opening of the package or crate, and that the several elements are readily capable of repeated use. Also, it is apparent according to both embodiments of the invention that by reason of the evenly spaced relation of the securing devices, the crate is readily adjustable both in length and width simply by a selective engagement of certain of the tongues 20 with certain of the slots 28, or by a selective alinement of the holes in the side and end elements with the holes in the corner elements for the reception of the bolts 34. Furthermore, according to both embodiments of the invention it is apparent that only a minimum amount of metal is required for the complete structure; that the corners of the structure are effectively reinforced by the corner elements, and that the production of the side and end elements is greatly simplified due to said elements being in all essential respects duplicates of one another.

Referring to the modification illustrated in Figure 7 it will be observed that the crating elements designated as 36 and corresponding to the elements 10 and 12 of Figs. 1 to 5, instead of being of U-shaped cross section like the elements 10, 12, are of L-shaped cross section. One of these elements 36 is arranged in embracing relation to each side and end corner of the articles to be packaged, and they are secured together by corner elements 14^a of substantially the same construction as the corner elements 14. That is to say, each element 36 is provided at its ends with a series of tongues 20^a, or with a series of bolt receiving openings as the case may be, and each corner element 14^a which is of U-shaped cross section and adapted to embrace the elements 36, is provided in each of the side walls thereof with two series of slots or openings for register with the tongues or bolt openings of the elements 36, to receive either the tongues 20^a or bolts, as the case may be, whereby the elements 36 and the corner elements are adapted to be interlocked.

Obviously, by reason of the arrangement illustrated in Fig. 7, a great saving in material may be effected over the use of crating elements of U-shaped cross section, particu-

larly in instances where the package is of material thickness. Obviously too, when crating elements of either **U**-shaped or **L**-shaped cross section are used the side and end sections may be formed either separately from one another or as a single continuous length of material suitably notched and bent to provide said side and end sections. Moreover, it is further obvious that as equivalents, 10 substantially, of the **L**-shaped crating sections, top and bottom plates may be provided to extend completely across the top and the bottom of the package and marginal flanges may be provided on said plates to 15 overlie the edges of the package and to be fastened to the corner elements in either of the different ways shown and described.

From the foregoing description considered in connection with the accompanying 20 drawing it is believed that the construction, mode of assembly and the advantages of my present packaging or crating structure will be clearly understood, it is desired to point out, however, that while certain specific embodiments of the invention have been illustrated and described herein, the same is capable of embodiment in specifically different mechanical structures within the spirit and scope of the invention as defined in the appended claims.

I claim:

1. A structure for packaging or crating articles comprising, in combination, straight side and end crating elements of **U**-shaped 35 cross section and entirely separate from each other to embrace the sides and the ends of the articles to be crated, said side and end crating elements having equal cross sectional dimensions, corner elements of **U**-shaped 40 cross section to embrace end portions of the side and end elements, and means for interlocking the corner elements with the side and end elements.

2. A structure for packaging or crating 45 articles comprising, in combination, separate side and end crating elements of **U**-shaped cross section and of equal sectional dimensions to embrace the sides and ends of the articles to be crated, **L**-shaped corner elements of **U**-shaped cross section to embrace end portions of the side and end elements, and a plurality of securing devices for fastening each corner element to one end of each of one of the side and one of the end elements, said securing devices being located at 55 evenly spaced points longitudinally of the respective corner and side and end elements for selective use to vary the effective length and width of the structure.

60 3. A structure for packaging or crating articles comprising, in combination, separate side and end crating elements of **U**-shaped cross section and of equal sectional dimensions to embrace the sides and ends of the articles to be crated, **L**-shaped corner elements

of **U**-shaped cross section to embrace end portions of the side and end elements, the side and end elements having tongue formations located at evenly spaced points longitudinally thereof, and the corner elements having slots located at points spaced longitudinally of said elements the same distance apart as said tongues to selectively receive the latter for interlocking the different elements together in different relations for varying the effective length and width of the structure.

4. A structure for packaging or crating articles comprising, in combination, separate side and end crating elements of **U**-shaped cross section and of equal sectional dimensions to embrace the sides and ends of the articles to be crated, corner elements of **U**-shaped cross section to embrace end portions of the side and end elements, said corner elements and the end portions of said side and end elements having holes evenly spaced longitudinally thereof for selective alinement, and bolts extending through said holes to secure the different elements in assembly with each other, the holes in the side and end elements being countersunk to receive the heads of the bolts,

5. A structure for packaging or crating articles comprising, in combination, separate side and end crating elements of **U**-shaped cross section to embrace the sides and the ends of the articles to be crated, **L**-shaped corner elements of **U**-shaped cross section each inclusive of angularly related portions to embrace an end of a side element and an end of an end element, respectively, and means for securing the respective portions of each corner element to the related end portions of a side and an end element in different relatively longitudinally adjusted positions of said corner portions and said side and end elements, respectively.

In testimony whereof I hereunto affix my signature.

HARRY C. WAY.
